UNITED STATES PATENT OFFICE.

GEORGE B. ROBBINS AND HARRY W. BELL, OF NEW YORK, N. Y.

TILE FOR COPING.

SPECIFICATION forming part of Letters Patent No. 374,705, dated December 13, 1887.

Application filed January 14, 1887. Serial No. 224,330. (No model.)

To all whom it may concern:

Be it known that we, GEORGE B. ROBBINS and HARRY W. BELL, both of the city and county of New York, in the State of New York, have invented a certain new and useful Improvement in Tiles for Coping, of which the following is a specification.

Our improved tile overcomes a difficulty experienced with the use of ordinary tiles, as adjacent buildings are constructed of different heights. When a brick building is completed, standing alone, with the wall at each end extending, as usual, a little above the roof, the coping-tiles should sit fairly on the tops of their respective walls, projecting over about equally outside and inside. When a higher building is run up alongside, it necessitates the removal of these tiles. Our invention allows them to be set anew on the same wall which they were originally placed on, a change in the position only being necessary to make them well adapted for the new conditions. To facilitate the removal without breaking, they should be set originally on the solitary wall with but little cement or mortar. On being lifted in preparing for the change only a very small proportion will be broken and require new to be applied. In the main the old tiles may be set on the wall, simply shifting them inward, so as to allow the next wall to be carried up smoothly past. The tiles on being shifted overhang entirely on the inner face of the wall. The change of position gives them a greater inclination. This is highly desirable, in order to carry away the increased quantity of rain-water which, with some directions of the wind, will come down from the perpendicular face of the adjacent wall. Our improved tile may be made in a continuous length by a tile-machine having a die with an aperture of the required form. This mode, which has long been practiced in making tiles for other purposes, being availed of for the production of a continuous length of our tile, the soft material is afterward cut by a stretched wire or otherwise into short lengths, the cut ends prepared by hand, and the thus-completed biscuit is dried and burned. This form allows the ends of adjacent tiles to match together with a rabbet. This insures that the tiles are held in the correct position.

The rabbet also favors the retention of a liberal quantity of mortar or cement to strongly unite the adjacent surfaces. The rabbeting may be effected by dexterously cutting along the edge with a suitable knife bent at right angles. It facilitates the manufacture and the burning without warping to make our tiles in pairs, the hollow or under sides being applied together.

The following is a description of what we consider the best means of carrying out the invention.

The accompanying drawings form a part of this specification.

Figure 1 is a vertical cross-section showing the tile laid as a coping on a wall standing alone. Fig. 2 shows the same wall with the coping-tile shifted in position to allow another wall to be carried up to a greater height alongside. Fig. 3 is a longitudinal section on the line $x-x$ in Fig. 1. It shows clearly the rabbets by which the adjacent tiles are joined. Figs. 4 and 5 are perspective views showing the adjacent ends of two tiles. Fig. 6 is on a larger scale. It is a cross-section showing two of the tiles in the process of manufacture.

Similar letters of reference indicate corresponding parts in all the figures where they occur.

A is the upper portion of the end wall of a brick building. A' is the adjoining wall of an adjacent building, built afterward and carried higher.

B is the main body of our coping-tile.

Certain portions are designated by additional marks, as B' B'', &c. B' is a hanging lip on the lower or inner edge of the tile. B'' is a hanging lip on the higher or outer edge of the tile.

A bearing-surface, b, is formed on the under side of the tile, adapted to bear on the inner edge of the wall. A bearing, b', extends along the mid-width of the tile. This is adapted to rest on the center of the wall.

Adjacent to the inner face of the lip B'' the material of the main body B is thickened considerably. Its lower edge forms a bearing-surface, b'', adjacent to the lip B''. A slight coating of cement or of common mortar applied continuously or at intervals under the coping-tiles holds them centrally on the wall.

A while it stands alone. The upper surface of the tile is slightly inclined. If the higher wall, A', is afterward built alongside, our coping-tiles are, as a preliminary step, lifted from their seats, which can be done after slightly jarring them. After the wall A' has been carried up past the top of A, our tiles are applied anew upon the top of the wall A; but in this case they are set so that the base of the lip B² 5 bears on the outer edge of the wall A adjacent to the higher wall, A'.

Cement may be applied in any quantities to make a firm coherence in this second laying of the tiles, as they are expected to remain 10 permanently attached under all future conditions.

We have in our experiments made the tiles in pairs, arranged as shown in Fig. 6, and propose to continue to do so. The form of

the die should be such that the two tiles forming a pair shall be joined just sufficiently to retain their positions in drying and burning, and yet allow the two tiles to be separated without destroying either tile. 20

We claim as our invention—

The coping B, having projections B' B², the latter forming an acute angle with the surface of the coping and abutting against a wall, substantially as set forth.

In testimony whereof we have hereunto set 30 our hands, at New York city, this 12th day of January, 1887, in the presence of two subscribing witnesses.
